UNITED STATES PATENT OFFICE.

WILLIAM COBURN AND CHARLES W. DAVIS, OF SEATTLE, WASHINGTON, ASSIGNEES
TO UNIVERSAL STERILIZING COMPANY, OF SEATTLE, WASHINGTON, A CORPOR-
ATION OF WASHINGTON.

WASHING-MACHINE.

1,179,505.

Specification of Letters Patent. Patented Apr. 18, 1916.

Application filed September 17, 1914. Serial No. 862,210.

To all whom it may concern:

Be it known that we, WILLIAM COBURN and CHARLES W. DAVIS, citizens of the United States, residing at Seattle, in the county of King and State of Washington, have invented certain new and useful Improvements in Washing-Machines, of which the following is a specification.

Our invention relates more particularly to a machine for washing tumblers and dishes, and it has for a main object to provide a novel washing chamber which may be opened for easy access to the articles therein and yet is adapted to be closed tightly to minimize leakage between the component parts of the chamber.

The above objects, and others which will appear from an inspection of the specification, we attain by the constructions shown in the drawings, described in the specification, and defined by the claims terminating the same.

In the accompanying drawings we have shown our invention embodied in a form which is now preferred by us, together with a modified construction.

Figure 1 is a top plan view of our improved washing machine. Fig. 2 discloses the same in side elevation with portions omitted. Fig. 3 is a view similar to Fig. 1 with several parts omitted to better illustrate the invention. Fig. 4 shows further the construction of the washing chamber, the same being a fragmentary vertical section taken on line 4—4 of Fig. 1. Figs. 5, 6 and 7 are sectional views taken respectively on lines 5—5 and 6—6 of Fig. 1 and line 7—7 of Fig. 2 to show the manner in which the meeting edges of the chamber sections are joined when closed. Fig. 8 discloses, partly in section, a modified form of our washing chamber as applied to a wash tank previously installed, and Fig. 9 is a horizontal section of the chamber taken on line 9—9 of Fig. 8.

Referring by like characters of reference to corresponding parts throughout, 1 designates the wash tank or receptacle supported by table 2 and provided with a drain or waste pipe 3. A spray nozzle 4, disposed in the lower part of the tank for discharging a fluid upwardly, is mounted on the con-

duit 5 which is connected by a three-way valve 6 to hot and cold water pipes 7 and 8 respectively.

A casing 9, superimposed upon the wash tank 1 and into which the spray from nozzle 4 is discharged, is composed of substantially semi-circular sections 10 and 11, the section 10 being fixedly joined to the tank while the component section 11 is pivotally connected to the fixed section by fastener 12 and constitutes a closure for the last section. An annular groove 13, encircling fixed section 10, forms a track or guide in which the semi-circular side wall of section 11 slides, the inner wall of the groove being perforated, as at 13', to effect a drainage thereof, as is obvious.

In the preferred embodiment of our invention, we have the movable section 11 slidable over the fixed one and the rear edges of the top and side walls 11' and 11'' respectively, turned inwardly to provide flanges or tongues 14 and 15, respectively, which are spaced from the walls and extend in the direction of closing movement to engage in the grooves or seats beneath the flanges 16 and 17 formed on the underlying top and side walls 10' and 10'' of the fixed section.

On the opposite edge portions of the top and side walls of the fixed casing section are provided outwardly spaced flanges 18 and 19 for forming seats to receive the forward edges of top and side walls 11' and 11'' respectively. It will therefore be noted that when the component sections constitute an inclosing casing, the joints between the sections are substantially leakage-proof. For opening and closing the movable section, we conveniently mount a handle 20 on the same.

Within the casing are mounted spaced rails 21 on which a basket or other foraminous support, for the articles being washed, is disposed. Fixed rails 22, on the table, extend longitudinally of the rails 21 and are adapted to receive the basket when removed from the washing chamber to permit of the articles thoroughly draining.

A drop table or shelf 23, pivoted in the elongated bearings 24 of the main structure for swinging to an inoperative position and constituting additional table surface, is sup-

ported in substantially the plane of the table 2 by braces 25 and surmounted by other rails 26 forming a continuation of rails 22.

In the modification, we make our casing 5 which constitutes the washing chamber, detachable from the wash tank, the former being provided with a circular flange or extension 27 depending from the annular guide 13 and formed with a seat 28 for supporting 10 the casing in place. This construction is especially adapted for application to wash tanks already installed, the conduit 5' being passed through the extension 27 immediately below groove 13 and above seat 28 and extended downwardly as in the preferred construction.

In operation, the tumblers, or other articles, are placed within the chamber upon the rails 21 and closure section 11 moved 20 into closed relation with the fixed section. Valve 6 is then operated, as by handle 6', to admit hot water to the chamber through nozzle 4 and, subsequent to shutting off this fluid, cold water is then admitted for an 25 interval for the rinsing purposes. After rinsing, the chamber is opened, and the articles removed to the table where they are allowed to drain.

The foregoing detailed description has 30 been given for clearness of understanding only, and no undue limitation is to be had therefrom, but the appended claims are to be construed as broadly as is permissible in view of the prior art.

35 Having thus described our invention, what we claim as new and desire to secure by Letters Patent of the United States of America, is:—

1. In a structure of the character described, a circular casing having a closure section pivoted concentrically thereto, a guide for the closure comprising a groove, one wall of which is provided with a drain opening, and flange means on the casing and 45 closure, the means on the latter interlocking with the means on the casing when the closure is in its operative position.

2. A dish-washing apparatus comprising a table and an annular casing secured thereto, 50 an annular groove in said table about the casing, said casing comprising a fixed half-section secured to the table and a complementary movable half-section, said sections being divided along an axial plane, and the 55 movable section being slidable in said annular groove in one direction over the fixed section, the top and side walls of each sec-

tion respectively being formed integral, and flanges upon one section adapted to interlock with complementary flanges upon the other section.

3. A dish-washing apparatus comprising a table and an annular casing secured thereto, an annular groove in said table about the casing, said casing comprising a fixed half-section secured to the table and a complementary movable half-section, said sections being divided along an axial plane, and the movable section being slidable in said annular groove in one direction over the fixed section, the top and side walls of each section respectively being formed integral, and a flange spaced from the diametrically opposite top and side edges of opposing sections, and adapted to fit over and engage flanges 75 upon the respectively adjacent edges of the opposing section.

4. A dish-washing apparatus comprising a table and an annular casing secured thereto, an annular groove in said table about the casing, said casing comprising a fixed half-section secured to the table and a complementary movable half-section, said movable section being slidable in said annular groove in one direction over the fixed section, drain openings in one wall of said groove, the top and side walls of each section respectively being formed integral and flanges upon one section adapted to interlock with complementary flanges upon the other section.

5. A dish washing apparatus comprising a table and an annular casing secured thereto, an annular groove in said table about the casing, said casing comprising a fixed half-section secured to the table, and a complementary movable half-section, said sections being divided along an axial plane, and the movable section being slidable in said annular groove in one direction relative to the fixed section, drain openings in the inner wall of said groove communicating with the interior of the casing, the top and side walls of each section respectively being formed integral and flanges upon one section adapted to interlock with complementary flanges upon the other section.

In testimony whereof we affix our signatures in presence of two witnesses.

WILLIAM COBURN.
CHARLES W. DAVIS.
